(57) **CLAIM**

The ornamental design for a tent, as shown and described.

DESCRIPTION

FIG. 1 is a top isometric view of an ornamental design for a tent;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom elevational view thereof;

FIG. 8 is an enlarged partial detailed view taken from the top of the tent in FIG. 1;

FIG. 9 is an enlarged partial detailed view taken from the right side of the tent in FIG. 1;

FIG. 10 is an enlarged partial detailed view taken from the bottom right of the tent in FIG. 1;

FIG. 11 is a top isometric view thereof in a partially opened configuration; and,

FIG. 12 is a top isometric view thereof in a fully opened configuration.

The broken lines are for the purpose of illustrating portions of the article that form no part of the claim. The dash-dot broken lines represent the boundaries of the enlarged partial views of FIGS. 8-10 and form no part of the claimed design.
